UNITED STATES PATENT OFFICE.

CARL A. WENDELL, OF JOLIET, ILLINOIS.

TAR-BURNER.

1,223,011.

Specification of Letters Patent. Patented Apr. 17, 1917.

Application filed October 21, 1916. Serial No. 1,27,005.

To all whom it may concern:

Be it known that I, CARL A. WENDELL, a citizen of the United States, residing at Joliet, in the county of Will and State of Illinois, have invented certain new and useful Improvements in Tar-Burners, of which the following is a specification.

My invention relates to apparatus for and a method of burning tar and has particular reference to novel constructions hereinafter more fully described.

While tar contains a relatively large number of heat units and has a high calorific value, its use as a fuel is not general because of the difficulties encountered in effecting complete combustion thereof. It has been found necessary to preliminarily heat the liquid to a high degree and then to atomize the same into a highly heated zone. This has, to a large extent, prevented the utilization of tar as a fuel for heating commercial boilers. When such attempt has been made, it has been common to inject the tar in a more or less atomized condition, into a firebox, upon the grate of which a bed of fuel is maintained. This is inconvenient, uneconomical in operation for the reason that the tar is not always burned to best advantage and requires constant attention.

30 An object in the present construction is to provide a burner so arranged as to act as a combustion unit, the mechanism shown acting to completely consume the tar which is employed as a fuel. The arrangement is such that a combustible gas, such as coke oven or natural gas, may be employed, first as a preheating agent and later as a continuously operating adjunct to the vaporizing and consuming of the injected tar.

40 The invention will be more readily understood by reference to the accompanying drawings, wherein—

Figure 1 is a longitudinal sectional view through a burner constructed in accordance 45 with my invention;

Fig. 2 is a sectional view on the line 2—2 of Fig. 1;

Fig. 3 is an enlarged fragmentary elevation of the tar spray nozzle, and

50 Fig. 4 is an end view of said nozzle.

The gas burner to which my novel tar burner is applied may comprise a cylindrical shell which forms a chamber 10. In the form shown, the cylinder is composed of two parts 11, 12, joined by cap bolts 13. The

outer end of the cylinder 11 is slightly contracted, as at 14, in order to control and define the flame as it issues from the mixing chamber 10. The extent of contraction will be determined by the size and shape of 60 the flame desired. Surrounding the cylinder 11 and spaced away from the same is a similarly shaped shell 15. The extremities of the shell are not connected to the cylinder, the same acting as a heating jacket for air 65 which is drawn in by the injective force of the flame issuing from the nozzle.

The portion 12 of the cylinder is surrounded by closed chambers 16, 17, the former of which is connected to a gas pipe 18 70 and the latter to a steam pipe 19. A plurality of spaced radial apertures 20 in the cylinder 12 connect the chamber 16 to the mixing chamber 10. A plurality of minute jet openings 21 connect the chamber 17 to 75 the mixing chamber 10. The jet openings 21 are inclined, both longitudinally and transversely of the axis of the mixing chamber 10. The purpose of the transverse or radial inclination is to enforce a whirling motion of the gases and a consequent more intimate mixture thereof. This is the sole purpose of utilizing the steam which is admitted through the pipe 19; that is, to enforce 80 a whirling motion. This result might be secured by the use of compressed air if desired. The end wall 22 of the mixing chamber is provided with a plurality of air entrance 85 openings 23. The burner just described is a complete operative economical gas burner 90 and may be employed singly if so desired. However, in order to utilize the same to best advantage, I prefer to associate therewith the tar burning apparatus which is illustrated. 95

The tar burning element comprises a long tube 24 inserted in the axial opening in the end wall 22 and held by a bracket 25 secured to the gas burner by cap bolts 26. At a point near the entrance end of the tube 24 100 a T 27 is located, providing a steam inlet 28 and a tar inlet 29. Within the T I provide an injector 30.

The outer end or nozzle of the tar injector is of peculiar construction, as best shown 105 in Figs. 3 and 4. The tube is flattened to form a nozzle shaped somewhat like a duck's bill, the exit orifice 31 of which is in the form of a narrow slot. A nozzle of this kind may be made with an exceedingly small 110

opening with less probability of becoming clogged or closed than a plurality of small apertures having the same area. It will be noted that the nozzle 32 for the tar is located exteriorly of the gas burner, the conduit for the tar, however, traversing the entire length of the mixing chamber. Therefore, the tar prior to being ejected from the nozzle 32 is highly heated, and upon being ejected instantly vaporizes, due to the inherent heat thereof and the heat of the flame within which it is atomized.

In an installation adapted for boilers, a burner such as shown is located in the firebox in a suitable manner, the grate bars being previously covered with fire brick laid fairly closely together so that a certain amount of air can be drawn in between them. In addition a wall of checkerwork is preferably built up at the end of the combustion chamber of the furnace in order to prevent the flame from striking the boiler tubes. In order to begin operations, the gas is turned on and burned alone until a certain heat is obtained in the combustion chamber. A small amount of tar is then admitted, together with steam to atomize the same, the amount of tar being increased as the temperature increases. Preferably the amount of gas employed will thereafter be reduced somewhat, as the heat of combustion of the tar will be sufficient. The tar employed is preferably preheated in a separate tank in order to make it more fluid and more easily atomized by the steam.

The arrangement is such that the atomized tar is not injected into the combustion space until it has been highly heated, the tar being atomized and injected into a space in which there is an excess of air. It is for this reason that the tar is not released until it is entirely outside of the gas burner. The whirling flame causes a vortex and the flat sheet of atomized tar is drawn into the vortex of heat and not released until combustion has been effected.

Both the method and apparatus may be varied somewhat and such modifications as will suggest themselves to those skilled in the art are considered to be within the spirit of my invention.

I claim:

1. The method of burning tar, which consists in mixing a readily combustible gas with air within a relatively confined space, causing said mixture to be ejected from said confined space with a whirling motion, conducting the tar through said mixing space, and ejecting said tar in a flat spray into said whirling body of burning gas at a point outside of said confined space, substantially as described.

2. The method of burning tar, which consists in combining combustible gas, steam and air in proper proportions within a cham-

ber, causing said mixture to be ejected from said chamber with a whirling motion, conducting the tar to be burned through said chamber by the use of steam, atomizing the tar and discharging the same at a point outside of said chamber and into the zone of complete combustion of said gas, substantially as described. 70

3. In a tar burner, the combination of a nozzle, admission ports at one end of said nozzle for gas, steam and air, said steam admission ports being longitudinally and transversely inclined and located in spaced relation around said nozzle whereby the gaseous mixture is given a whirling motion, and an axial conduit terminating in a flat spray nozzle at a point outside of said first-named nozzle, substantially as described. 75

4. In a tar burner, the combination of a cylindrical shell providing a plurality of spaced entrance ports for gas, steam and air, a plurality of said ports being disposed at an angle to longitudinal and transverse lines, whereby the mixture is caused to whirl, a tar inlet tube disposed axially of said cylinder, said tube terminating in a flat spray nozzle at a point exterior to said cylinder, and a steam injector located in said tar tube, substantially as described. 80

5. In a device of the class described, the combination with a cylinder having jackets at one end, of a pipe, one of said jackets being for gas and the other for steam, said cylinder being provided with openings connecting said gas jacket with the interior of said cylinder and also connecting the interior of said steam jacket with said cylinder, the latter openings being angularly disposed with respect to the longitudinal and transverse axes of said cylinder, a perforated end member positioned in the cylinder at the jacketed end thereof, said pipe extending through said cylinder and having a restricted wedge-shape mouth piece, whereby matter passing therethrough is caused to issue in fan-like manner, substantially as described. 95 100 105 110

6. A tar burner, comprising in combination a cylinder and a pipe, the cylinder being of substantial diameter, a perforated end member for one end thereof, the other end of the cylinder being slightly smaller in diameter than the diameter of said cylinder, jackets about the cylinder near the perforated end member, the cylinder being provided with openings connecting the interior of the jackets with the interior of the cylinder, the disposition of the openings connecting the interior of one jacket with the cylinder being angularly arranged with respect to the longitudinal and transverse axes of the cylinders, a shell surrounding the smaller end portion of such cylinder, said pipe extending through said cylinder and projecting be- 115 120 125 130

yond the end thereof, the end of the pipe having a wedge-shape point and a fan-like opening, substantially as described.

7. A tar burner, comprising in combination a gas burning member and a tar spray member, the gas burning member comprising a cylinder having one end covered by a perforated plate, the other end slightly reduced in diameter, a steam jacket and a gas jacket surrounding the cylinder at the closed end, the jackets being out of communication with one another, the cylinder being provided with a series of apertures connecting the steam jacket and the interior of the cylinder which are angularly disposed with respect to the longitudinal and transverse axes

of said cylinder, the cylinder being provided with another series of apertures connecting the interiors of the gas jacket and the cylinder, inlet openings in said jackets, the tar spray comprising a pipe extending through the cylinder and having a restricted wedge-shape end with a slotted opening, said end positioned slightly beyond the smaller end of said gas burning member, substantially as described.

Signed at Joliet, Illinois, this 16th day of October, 1916.

CARL A. WENDELL.
